UNITED STATES PATENT OFFICE.

DANIEL B. HISER, OF WOOSTER, OHIO.

BURIAL-CASKET.

SPECIFICATION forming part of Letters Patent No. 288,804, dated November 20, 1883.

Application filed August 17, 1883. (Model.)

To all whom it may concern:

Be it known that I, DANIEL B. HISER, of Wooster, in the county of Wayne and State of Ohio, have invented a new and Improved Burial-Casket, of which the following is a full, clear, and exact description.

The object of my invention is to provide a new and improved metallic burial-casket which has all the bolts in the bottom and top rim, so that none will show in the sides or ends.

The invention consists in a metallic burial-casket constructed with side pieces and end pieces united by screws passed through the top and bottom rims or flanges, so that none of the screws or bolts will appear on the sides or ends of the casket.

The invention also consists in the construction of various other parts and details, and combinations of the same, as will be fully described and set forth hereinafter.

Reference is to be had to the accompanying drawings, forming part of this specification, in which similar letters of reference indicate corresponding parts in all the figures.

Figure 1 is a longitudinal elevation of my improved burial-casket, parts being broken out and others shown in section. Fig. 2 is a plan view of the same, parts being broken out.

Fig. 3 is a cross-sectional elevation of the same on the line *x x*, Fig. 1.

The sides *A* of the casket are each provided with an outwardly and inwardly projecting flange, *A'*, at the top, and an inwardly-projecting flange, *A''*, at the bottom. The end pieces, *B*, are also provided with top and bottom flanges, *B'* and *B''*, respectively, and the ends of the end pieces are rounded, so that they will fit against the ends of the side pieces, and the ends of the flanges of the end pieces will fit against the ends of the flanges of the side pieces. The end edges of the side pieces, *A*, and the end pieces, *B*, are rabbeted, and the bottom flanges, *A''*, of the side pieces, *A*, are provided on the upper surface with lugs *C*, adapted to overlap the ends of the bottom flanges, *B''*, of the end piece, *B*, as shown in Figs. 1 and 2, and then bolts *c* are passed through the said lugs *C* and the ends of the flanges *B''*, which bolts have their heads countersunk in the bottom surfaces of the flanges *B''*, and have nuts resting on the lugs *C*. The top flanges *A'* of the side pieces are provided

on the inwardly-projecting part and each end with a lug, *C'*, which passes under the corresponding end of the top flange *B'*, a bolt, *c'*, being passed through the end of the flange *B'* and the lug *C'*, which bolt *c'* has its head countersunk in the upper surface of the flange *B'*. The ends are then united with the side pieces, and the heads of the bolts show on the top and bottom surfaces of the casket, the nuts being in the interior of the same. The bottom plate, *D*, of the casket is placed against the under surfaces of the bottom flanges, *A'' B''*, of the side pieces, *A*, and end pieces, *B*, respectively, and is secured to the same by bolts *b*, having their heads countersunk in the under surface of the bottom plate, the nuts resting on the upper surface of the bottom flanges *A''* of the side pieces. By uniting the sides, ends, and bottom of the casket in this manner, no bolts will show on the sides or ends, and the countersunk heads only of the bolts will show on the under surface of the bottom plate, *D*, and the nuts on the top surfaces of the flanges *A' B'*. That part of the flanges *A' B'* projecting outward is provided with a groove, *a*, for receiving the packing or cement, thus forming close joints. Wooden strips *E* are held in the upper surfaces of the bottom flanges *A''* by studs *F*, projecting upward from the lugs *C*. Wooden strips *G* are held on the under sides of the inwardly-projecting parts of the flanges *A'* by screws *d*, countersunk in the upper surfaces of the flanges *A'* and screwed into the wooden strips *G*. The lining of the casket is tacked to the said wooden strips. Wooden strips *G'* are secured to the under sides of the flanges *B''* of the end pieces. The cover *H* is provided on its side and end edges with downwardly-projecting flanges *H'*, which fit over the edges of the outwardly-projecting parts of the flanges *A' B'*. Glass panes *I* are held in the top of the cover, the panes fitting between downwardly-projecting ridges *J* on the under side of the cover. The ridges *J* are provided with lugs *J'*, through which screws *K* are passed, which have nuts resting against the outer surfaces of the lugs *J'*, and heads against the inner surfaces of the lugs and the ridges *J*. Wooden wedges *L* are forced in between the edges of the bolts *K* and the under surfaces of the panes of glass, *I*, and thus hold the panes in place.

The sides A and their top and bottom flanges A' A² are cast in one piece, as also are the ends B with their top and bottom flanges B' B², so that the casket will be composed of six pieces—that is, two sides, two ends, top, and bottom.

Having thus described my invention, I claim as new and desire to secure by Letters Patent—

1. A metallic burial-casket constructed with flanged side and end pieces, the flanges of the side pieces being provided at the ends with lugs projecting beyond the ends of the flanges, and lapping the flanges of the end pieces, said end-piece flanges projecting under the said lugs, through which lugs and the ends of the flanges of the end pieces screws are passed, for

uniting the end pieces with the side pieces, substantially as herein shown and described, and for the purposes set forth.

2. In a metallic burial-casket, a cover provided with downwardly-projecting ridges J on the under side, which ridges have lugs J', a glass plate, I, held between the ridges, the bolts K, passed through the lugs J', and the wedges L, driven in between the glass and the heads of the bolts, substantially as herein shown and described, and for the purpose set forth.

DANIEL B. HISER.
